UNITED STATES PATENT OFFICE

JOE ASBURY AND EARL R. AUSTIN, OF BRECKENRIDGE, TEXAS

BANDALORE TOY

Application filed July 26, 1929. Serial No. 381,277.

This invention relates to improvements in bandalore toys of the type disclosed in the U. S. Letters Patent to Streisguth and Schnitzler, No. 279,888, dated June 19, 1883.

5 The primary object of the present invention is to provide a toy of the above kind in which fans or screw impeller blades are mounted at opposite side of the roller and adapted to rotate with or relative to the latter to add to the attractiveness of the toy.

10 Other objects will appear as the nature of the invention is better understood, and the same consists in the novel form, combination and arrangement of parts hereinafter more 15 fully described, shown in the accompanying drawings, and claimed.

In the drawings:

Figure 1 is a front elevation of a toy embodying the present invention.

20 Figure 2 is a section on line 2-2 of Figure 1.

Figure 3 is a side elevation of the toy shown in Figure 1, with the cord broken away.

25 Figure 4 is a vertical section on line 4-4 of Figure 3.

Figure 5 is a view similar to Figure 1 of a modified form of the toy.

Figure 6 is a view similar to Figure 5 with 30 the curved impeller blades reversed.

Figure 7 is a view similar to Figure 4 of the toy shown in Figure 6; and

Figure 8 is a side elevation of the toy shown in Figure 6.

35 Referring in detail to the drawings, the present toy embodies the usual roller formed of side disks 5 and a connecting hub 6, the latter having one end of a cord 7 secured thereto for spinning the roller in a well known manner.

In accordance with the present invention, fans or screw impellers 8 are mounted at opposite sides of the roller with their axes coincident with the spinning axis of said 40 roller.

In the form of the invention shown in Figures 1 to 4 inclusive, the roller has a fixed axial pin 9 whose end projects at opposite sides of the roller and have the fans 8 mounted thereon, caps 10 being frictionally fitted

on the ends of the pin 9 outwardly of the fans to retain the latter in place. By setting the caps 10 to barely engage the fans, the latter may be left free to turn on the pin 9 relative to the roller, thus relying mainly on 55 the action of the air on the fans to turn the same when the roller spins and swings back and forth during the operation of the toy. However, by tightening the caps 10, the fans may be clamped between the same and the 60 sides of the roller to turn therewith, thus causing the latter to move laterally when in operation. In either event, the action and rotation of the fans will present an attractive appearance and furnish added amusement to 65 the child using the toy.

The disks 5 are preferably of convex form on their outer faces, and as shown in Figure 5, the fans or impellers 8a may be of longitudinally curved form and arranged to conform to the curvature of such faces. This presents a compact construction in which damage to the fans is rendered unlikely, and screws 11 may be removably threaded into the sides of the roller to support the fans. By 70 removing the screws 11, the position of the blades may be reversed as shown in Figures 6 to 8 inclusive, wherein the blades are disposed with ends curving outwardly from the sides of the roller. This will enhance the 75 attractiveness of the toy by sacrificing protection of the fans and in either case the screws 11 may be adjusted to allow the fans to turn freely thereon relative to the roller or tightened to cause them to turn with the roller, 80 as desired.

In use, the cord 7 is wound on the hub 6 and then the free end of the cord is held when the roller is dropped. The roller is thus rapidly rotated by the unwinding of the cord 90 therefrom, and when the cord is completely unwound, the cord is given a slight upward pull for causing the roller to again wind upon the cord. The operation may be continued indefinitely, and the rotating fans will 95 furnish a variation of action and appearance constituting a highly amusing feature of the toy.

Changes in the form and character of the fans and their specific mode of attachment 100

are contemplated within the spirit of the invention.

What we claim as new is:

1. In a bandalore toy, the combination of
5 a roller formed of side disks and a connecting
hub, a cord attached at one end to the
hub, and rotary fans mounted at opposite
sides of the roller with their axes coincident
10 with the axis of rotation of the roller, said
side disks having convex outer sides, said
fans being longitudinally curved to follow
the contour of said sides of the disks.
2. In a bandalore toy, the combination of
15 a roller formed of side disks and a connecting
hub, a cord attached at one end to the
hub, rotary fans mounted at opposite sides of
the roller with their axes coincident with the
axis of rotation of the roller, said side disks
20 having convex outer sides, said fans being
longitudinally curved to follow the contour
of said sides of the disks, and means to re-
movably mount the fans at the outer sides of
the roller to permit reversal of the fans with
respect to said roller.
- 25 In testimony whereof we affix our signatures.

JOE ASBURY.
EARL R. AUSTIN.
